(57) **CLAIM**

The ornamental design for a compact disc cleaner, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is the front view of the compact disc cleaner of the present invention;

FIG. 2 is top plan view thereof;

FIG. 3 is a rear view thereof;

FIG. 4 is a side view of the invention, the view of the other

side being a mirror image thereof; and,

FIG. 5 is a bottom plan view.
